UNITED STATES PATENT OFFICE.

JOHN P. BUCHANAN, OF CLEVELAND, OHIO, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,140,495.

Specification of Letters Patent. Patented May 25, 1915.

Application filed January 22, 1915. Serial No. 3,739.

To all whom it may concern:

Be it known that I, JOHN P. BUCHANAN, a citizen of the United States, residing at Cleveland, in the county of Cuyahoga and State of Ohio, have invented certain new and useful Improvements in Railway Signaling, of which the following is a specification.

My invention relates to railway signaling, and particularly to automatic signaling of the type in which the signal for each block is adapted to give three indications, viz., "proceed", "caution", and "stop".

More particularly it relates to signaling of this type in which each signal is controlled by apparatus responsive to reversals of current, the reversals being accomplished by the signal for the block next in advance. It is well understood by those skilled in the art that the circuit for the reversible current for the signal controlling apparatus may include the track rails or may include line conductors distinct from the track rails, the former being known in the art as a "polarized track circuit", and the latter as a "polarized line circuit". One feature of my invention is the provision of apparatus which may be operated either on the polarized track circuit principle or on the polarized line circuit principle. Then, if the line circuit is deranged, as for example due to broken line wires, the system may be operated as a polarized track circuit system until the necessary repairs have been made.

I will describe two forms of signaling systems embodying my invention, and will then point out the novel features thereof in claims.

In the accompanying drawings, Figure 1 is a diagrammatic view showing one form of signaling system embodying my invention, each block comprising only one track section. Fig. 2 is a view showing a modified form of signaling system embodying my invention, each block comprising more than one track section.

Similar reference characters refer to similar parts in each of the views.

Referring first to Fig. 1, I have here shown a railway track over which traffic moves in the direction of the arrow, which track is divided into block sections A, B, etc. by any one of the well known means, such as insulated joints 3 in the track rails 1 and 2. Block signals S^A, S^C, etc. of any

of the well known types are located at the entrances to the blocks, these signals as here shown being of the semaphore type and each being capable of giving three indications; namely, "stop", "caution" and "proceed". As here shown, each signal is of the one-arm three-position type, although it is understood that two-arm, two-position signals may equally well be used. Each block section is equipped with the usual track circuit consisting of a source of electromotive force, the track rails and a relay. The sources of electromotive force I have shown to be batteries E^A, E^B, etc. located at one end of each block section. The track relays located at the other ends of the sections are of the polarized type, and are designated by the reference characters R^B, R^C, etc. For each block I also provide a line relay of the polarized type located adjacent the signal at the entrance to the block and designated by the reference characters M^B, M^C, etc. Pole changers G^B, G^C, etc., are operatively connected with the block signals and serve to control the polarity of the track circuit or the line circuit as hereinafter explained. Batteries V^B, V^C, etc., are provided for supplying the operating mechanisms or signals S^B, S^C, etc., with the necessary electrical energy, whereas batteries B^A, B^B, etc., are for the purpose of supplying electrical energy to the line circuits. In practice, the two batteries B and V could equally well be one and the same battery. Furthermore, for each block section I provide three double-pole, double-throw switches K^A, K^B, etc., L^A, L^B, etc., and N^B, N^C, etc., and a double pole single throw switch H^A, H^B, etc.; all of these switches are as here shown arranged for operation by hand.

Assuming first that the manually operable switches are in the positions shown, then the signaling system is a polarized line system, as the following description will show. Considering block B, for example, the track circuit is supplied with signaling current by battery E^B, one terminal of which is connected to rail 1 through wire 71, blade 10 of switch H^B, and wire 65, and the other terminal of which battery is connected to rail 2 by means of wire 73, blade 11 of switch H^B, and wire 66. If the track rails of section B are unoccupied by a train or car, the signaling current will energize the track relay R^B by flowing from rail 1 through wire 23, en-

- ergizing winding of relay R^B , wire 22 to rail 2. Relay R^B attracts its armature, whereby neutral contacts 44-47, 45-48, and 46-49 are closed. Contacts 45-48 and 46-49 of relay R^B close the following circuit: from battery B^B , through wire 19, blade 21 of knife switch K^B , wire 70, blade 6 of pole-changer G^C , wire 78, blade 30 of switch L^B , wire 79, contact 45-48 of relay R^B , wire 85, energizing winding of relay M^B , wire 86, contact 46-49 of relay R^B , wire 80, blade 31 of switch L^B , wires 77 and 75, blade 5 of pole-changer G^C , wire 69, blade 20 of switch K^B , wire 18 to battery B^B . Thus line relay M^B is energized, so that contact 50-51 closes the following circuit: from battery V^B , through wire 89, operating mechanism of signal S^B , wire 82, contact 50-51 of relay M^B , wire 88, blade 127 of switch N^B , wire 125 to battery V^B . Assume that contact 53-52 of relay M^B is closed when the direction of current through the energizing winding of this relay is such as is indicated on the drawing by the polarity of battery B^B and the position of pole-changer G^C , which I shall call the normal position of the pole-changer. When contact 53-52 of relay M^B is made, the following circuit is closed: from battery V^B through wire 89, operating mechanism of signal S^B , wire 81, blade 128 of switch N^B , wire 126, contact 53-52 of relay M^B , wire 87, contact 50-51, wire 88, blade 127 of switch N^B , wire 125 to battery V^B .
- I have not shown the operating mechanisms of the signals, for I assume these mechanisms any of the well known types. Suffice it to say that the circuit closed by contact 50-51 of each relay M is called the 45 degree control circuit, which means that when this circuit is closed the operating mechanism of signal S^B drives the semaphore arm 4, normally biased to a horizontal position indicating "stop," to a position at an angle of about 45° from the horizontal, which aspect of the signal is called "caution." When contact 52-53 of relay M^B is also closed, then the 90° control circuit of the signal is closed, which means that the signal mechanism drives the semaphore arm 4 so as to be at about 90° from the horizontal, giving the so-called "proceed" aspect of the signal. When a train enters block B, it short circuits relay R^B by forming a low resistance path for the signaling current from rail to rail through the car wheels. Thus relay R^B is deenergized, its armature drops and opens its contact 44-47, 45-48, 46-49. The energizing circuit of relay M^B is thereby broken and contact 50-51 of relay M^B opens both the 90° and 45° control circuits of signal S^B . Semaphore arm 4 of signal S^B thus drops to the horizontal position, indicating "stop" to the engineer of a following train. As the

train passes into block C it puts signal S^C to the stop indication by the same sequence of operation of the relays for block C. When the last pair of car wheels of the train leave block B the short circuit across the track rails of block B is removed and relay R^B is again energized, so that the neutral contacts of this relay again close. Thus current is again furnished to relay M^B , but the polarity of this current is opposite in direction to the direction assumed above, for pole-changer G^C operated by semaphore blade 4 of signal S^B was reversed as the arm passed through the 45°-0° part of its stroke. Hence relay M^B closes only contact 50-51, or the 45° control circuit of signal S^B , which is thus moved to the caution aspect, where it stays as long as the train is in block C. When the train enters block D it puts signal S^D to the stop position, and when it has left block C entirely, signal S^C is moved to the caution indication by an operation of the apparatus similar to that described hereinbefore. As the semaphore arm 4 of signal S^C goes to the caution or 45° position it again operates the pole-changer G^C , returning it to the normal position. Thus the current through relay M^B is again normal in direction so that contact 52-53 closes, thus closing the 90° control circuit of signal S^B , which causes this signal to assume the proceed aspect.

The above description shows that my system operates as a polarized line system when the switches H, K, L and N are in the positions indicated on the drawing. When switches K, L and N are reversed and switches H are opened my system will operate as follows: Consider again block section B. By opening switch H^B and reversing switches L^B and K^B , battery E^B is connected across the rails 1, 2 through pole-changer G^C , the connections being: from one terminal of battery E^B through wire 74, blade 21 of switch K^B , wire 70, blade 6 of pole-changer G^C , wire 78, blade 30 of switch L^B , wires 67 and 66 to rail 2, and from the other terminal of battery E^B through wire 72, blade 20 of switch K^B , wire 69, blade 5 of pole-changer G^C , wires 75 and 77, blade 31 of switch L^B , wires 68 and 65 to rail 1. Thus signaling current flows through the track rails 1, 2 and, as long as the track is unoccupied, through relay R^B , which attracts its neutral armature and closes therefore its contacts 44-47, 45-48 and 46-49. The closure of contacts 45-48 and 46-49 is immaterial, because the control of the circuits for signal S^B has been transferred from relay M^B to relay R^B by switch N^B . Contact 44-47 of relay R^B closes the 45° control circuit of the signal S^B , which circuit is: from battery V^B through wire 89, operating mechanism of signal S^B , wires 82 and 83, contact 44-47 of relay R^B , wire 97, blade 127 of

switch N^B , wire 125 to battery V^B . Assuming that the direction of the current in relay R^B is such that polarized contact 54-55 closes, this contact closes the 90° control circuit of signal S^B , causing current to flow from battery V^B , through wire 89, operating mechanism of signal S^B , wire 81, blade 128 of switch N^B , wire 84, contact 54-55 of relay R^B , wire 33, contact 44-47 of relay 10 R^B , wire 97, blade 127 of switch N^B , wire 125 to battery V^B . Thus, under conditions as assumed above the signal S^B at the entrance to block B gives a "proceed" indication. When a train enters block B, it short circuits relay R^B , the neutral contacts of which drop, thereby opening both the 45° and the 90° control circuits of signal S^B , so that this signal changes to the "stop" indication. When the train enters block C, the aspect of 15 signal S^C is changed from "proceed" to "stop." Then, as semaphore arm 4 of signal S^C goes through the 45° to 0° portion of its stroke, it reverses pole-changer G^C , which as pointed out above is operatively connected with arm 4 of signal S^C . Thereby the direction of the flow of the signaling current in the track rails of block B is changed, so that when the rear end of the train leaves block B, removing the short circuit from 20 relay R^B , this relay closes its neutral contacts, but the polarized contact 54-55 remains open. Thus current is furnished only to the 45° control circuit and the signal S^B is caused to give the "caution" indication. 25 Similarly when the train enters block D, signal S^D assumes the stop aspect; and as the train leaves block C completely signal S^C assumes the caution aspect. But, as the semaphore arm 4 of signal S^C moves from 30 0° to 45° it again reverses pole-changer G^C , whereby the direction of the flow of signaling current through block B is again made normal. This causes contact 54-55 of relay R^B to close the 90° control circuit of signal 35 S^B . Thus signal S^B is caused to give the clear indication.

The above description shows that with the switches in the positions assumed my system operates on the polarized track circuit principle.

Referring now to Fig. 2, I have here shown a modified form of signaling system wherein the block sections A, B, etc. are divided into sub-sections A^1 and A^2 , B^1 and B^2 , etc., by means of additional insulated rail joints 3. In addition to the apparatus used in Fig. 1 each block is provided with another track relay P^B , P^C , etc., which has a polarized and a neutral armature, the former actuating contact fingers 60 and 63, the latter controlling contact fingers 56 and 57, another track battery E^B , E^C , etc., and another double pole, double throw switch W^B , W^C , etc. To describe the operation of this 60 system, assume the switches H, K, L, N and

W for each section to be in the positions indicated on the drawing. Consider first block section B. Sub-section B' is equipped with a track circuit which is supplied with signaling current by battery E^B , one terminal 70 of which is connected to track rail 1 through wire 39, switch blade 43 of switch W ^{B} and wire 90, and the other terminal of which is connected to rail 2 through wire 38, switch blade 42 of switch W ^{B} and wire 91. As 75 long as there is no train in sub-section B', relay R^B is energized by the signaling current furnished by battery E^B , the connections between the relay and the rails being the same as shown in Fig. 1. In sub-section 80 B ^{2} the track circuit is supplied with signaling current by battery E^B connected to the rails at one end of the sub-section in the same manner as in Fig. 1. Relay P^B , connected to the track rails at the other end of 85 sub-section B ^{2} by wires 102 and 103, is energized by this current when there is no train in sub-section B ^{2} . Thus relay P^B closes its contacts 56-58 and 57-59, thereby closing the circuit: from battery B^B , wire 18, switch 90 blade 20 of switch K ^{B} , wire 69, blade 5 of pole-changer G^C , wires 75 and 77, blade 31 of switch L ^{B} , wire 80, contact 46-49 of relay R^B , wire 86, energizing winding of relay 95 M ^{B} , wire 85, contact 45-48 of relay R^B , wire 96, contact 56-58 of relay P^B , wire 92, wire 79, blade 30 of switch L ^{B} , wire 78, blade 6 of pole-changer G^C , wire 70, blade 21 of switch K ^{B} , wire 19 to battery B^B . Thereby line relay M^B of block B is energized and 100 closes contact 50-51. Assume also that the direction of the current through relay M^B is normal, so that its polarized armature closes the contact 53-52. Then both the 45° and the 90° control circuits of signal S^B are closed 105 as described in Fig. 1, so that signal S^B is caused to give the "proceed" indication. Now, when a train moving in the direction of the arrow enters block B, it short circuits relay R^B , which releases its neutral 110 armature and opens the energizing circuit of relay M^B at contacts 45-48 and 46-49. Relay M^B is thus deenergized and opens both the 45° and the 90° control circuits of signal S^B at contact 50-51. Consequently 115 signal S^B releases its arm 4, which swings to the horizontal position and indicates "stop." As the train proceeds into sub-section B ^{2} of block B it short circuits relay P^B which is deenergized thereby, so that this relay releases its neutral armature and opens contact 56-58. (The other contacts of relay 120 P^B have no function when the system is operated on the polarized line circuit principle, and are not mentioned here for that reason). Thus, even though relay R^B is reenergized as the rear of the train leaves sub-section B ^{2} , and closes contacts 45-48 and 46-49, relay M^B is not energized because its 125 circuit is broken at contact 56-58 of relay 130

P^B , and signal S^B retains its "stop" aspect until the train leaves block B. When the train enters block C, it causes signal S^C to indicate "stop" through an operation of relays similar to that explained for block signal S^B . Pole-changer G^C reverses the direction of flow of the line current, so that when the train leaves sub-section B^2 and relay P^B closes the line circuit at contact 56—58, relay M^B is supplied with current flowing in reverse direction, which causes it to close contact 50—51 and to open contact 53—52. Thus only the 45° control circuit of signal S^B is closed and this signal assumes the "caution" aspect. Similarly, when the train enters block D it causes block signal S^B to indicate "stop." And as it leaves block C completely it causes signal S^C to assume the caution aspect. In doing so, the semaphore of signal S^C operates the pole-changer G^C , which makes the direction of the current flowing in the line circuit of block B normal. Relay M^B closes contact 53—52 and completes thereby the 90° control circuit of signal S^B . Hence signal S^B assumes the "proceed" indication. Thus, with the manually operable switches in the position shown in Fig. 2, the signaling system operates as a polarized line system.

When the switches K, L, N and W are reversed and the switches H are opened, then the signaling system operates as follows: In block B, the track circuit of sub-section B^2 is supplied with signaling current by battery E^B , one terminal of which is connected to rail 1 by wire 72, blade 20 of switch K^B , wire 69, blade 5 of pole-changer G^B , wires 75 and 77, blade 31 of switch L^B and wires 68 and 65, and the other terminal of which is connected to rail 2 by wire 74, blade 21 of switch K^B , wire 70, blade 6 of pole-changer G^B , wire 78, blade 30 of switch L^B and wires 67 and 66. Assume the direction of flow of this current to be such that the polarized armature of relay P^B will swing contact fingers 60 and 63 to the left, so as to close contacts 61—60 and 62—63. Battery E^B then furnishes signaling current to the track circuit of sub-section B' , one terminal being connected to rail 1 by wire 38, blade 42 of switch W^B , wire 93, contact 57—59 of relay P^B , wire 94, contact 62—63 of relay P^B , wires 98 and 90, and the other terminal being connected to rail 2 by wire 89, blade 43 of switch W^B , wire 92, contact 56—58 of relay P^B , wire 95, contact 61—60 of relay P^B , wires 100, 99 and 91. Assume the polarity of this current to be such that, when there is no train in sub-section B' , relay R^B is energized normally, *i. e.* both the neutral and the polarized contacts are closed. Then the 45° and the 90° control circuits of signal S^B are closed as described in Fig. 1, whereby signal S^B is caused to give the "proceed" indication. When a train moving in the direction

of the arrow enters block B, relay R^B is short circuited and opens both the 90° and 45° control circuits of signal S^B at contact 44—47. Thus semaphore arm 4 of signal S^B is released and drops to the horizontal position. As the train enters sub-section B^2 of block B, it short circuits relay P^B , which opens contacts 56—58 and 57—59, breaking thereby the connection of battery E^B to the track rails. Relay R^B thus remains open so that signal S^B continues to indicate "stop." As the train enters block C it causes signal S^C to assume the stop indication. At the same time pole-changer G^C is reversed, so that the signaling current, which again flows in relay P^B as the train leaves sub-section B^2 entirely, is reversed in direction. Hence the polarized armature of relay P^B causes contact fingers 60 and 63 to swing to the right, whereby the connections of battery E^B to the track rails are reversed. Consequently signaling current flows in the track circuit of sub-section B' in the opposite direction, and relay R^B closes contact 44—47, but opens contact 54—55. Thus only the 45° control circuit of signal S^B is closed, which causes the signal to assume the "caution" aspect. Similarly, as the train enters block D, it puts the signal S^D for that block to the stop indication, thus reversing pole-changer G^D , which controls the direction of flow of signaling current in section C^2 . Relay P^C then closes, hence signal S^C is caused to assume the caution aspect. Thereby the pole-changer G^C is thrown into its normal position and the direction of flow of signaling current in sub-section B^2 is again reversed so that contact fingers 60 and 63 of relay P^B are shifted to make contact to the left. Thus current through sub-section B' is reversed, causing relay R^B to close the 90° control circuit of signal S^B at contact 54—55, whereby signal S^B is returned to the proceed indication.

The above description shows that the signaling system with the various manually operable switches in the positions specified operates on the polarized track circuit principle.

Although I have herein shown and described only two forms of signaling system embodying my invention, it is understood that various changes and modifications may be made therein within the scope of the appended claims without departing from the spirit and scope of my invention.

Having thus described my invention what I claim is:

1. In combination, a section of railway track, a track circuit and a line circuit for the section, a signal for the section, and means for controlling said signal by the track circuit alone or by the track circuit and the line circuit.

2. In combination, a section of railway

track, means for dividing the same into sub-sections, a track circuit for each sub-section, a line circuit for the section, a signal for the section, and means for controlling said signal by the track circuits alone or by the track circuits and the line circuit.

3. In combination, a section of railway track, a track circuit for the section including a track relay responsive to reversals of current, a line circuit extending through the section and controlled by said track relay and including a line relay responsive to reversals of current, means for supplying current to either the track circuit alone or to both the track circuit and the line circuit, means for reversing the current in the track circuit when current is supplied to the track circuit only and for reversing the current in the line circuit when current is supplied to both circuits, a signal for the section, and means for controlling said signal by the track relay or by the line relay according as the track circuit alone is energized or both circuits are energized.

4. In combination, a section of railway track divided into sub-sections, a track circuit for each sub-section including a track relay responsive to reversals of current, a line circuit extending through the section and controlled by the track relays of the sub-sections and including a line relay responsive to reversals of current, means for all sub-sections except the last in advance for supplying current to the corresponding track circuits, means comprised in each track relay for reversing the flow of current in the track circuit for the next sub-section in the rear, means for supplying current to either the track circuit of the last sub-section alone or to both the said track circuit and the line circuit, means for reversing the current in the last-mentioned track circuit when current is supplied to the track circuit only and for reversing the current in the line circuit when current is supplied to the track circuits and the line circuit, a signal for the section, and means for controlling said signal by the track relay of the first sub-section or by the line relay according as the track circuits alone are energized or both the line circuit and the track circuits are energized.

5. In combination, a section of a railway track, a track circuit for the section including a track relay responsive to reversals of current, a track battery, a line circuit for the section controlled by said track relay and including a line relay responsive to reversals of current, a line battery for the line circuit, a pole-changer, switches and conductors for connecting the track battery directly with the track rails and the line battery with the line circuit through the pole-changer, or for disconnecting the line battery from the line circuit and connecting the track battery with the track rails through the pole-changer, a

signal, and means for controlling said signal by the track relay or by the line relay.

6. In combination, a section of a railway track which section is divided into sub-sections, a track circuit for each sub-section including a track relay responsive to reversals of current, a track battery for each sub-section, a line circuit extending through the section and controlled by a neutral contact of each track relay, said line circuit including a line relay responsive to reversals of current, a line battery for the line circuit, a pole-changer, switches and conductors for connecting the track battery for the sub-section farthest in advance directly with the track rails and the line battery with the line circuit through the pole-changer, or for disconnecting the line battery from the line circuit and connecting the last-mentioned track battery with the track rails through the pole-changer, means for connecting each remaining track battery directly with the track rails of the corresponding sub-section or for connecting each of said remaining track batteries with the track rails through contacts of the track relay for the sub-section in advance said contacts constituting a pole-changer, a signal for the section, and means for controlling said signal by the track relay for the rear sub-section or by the line relay.

7. In combination, a railway track divided into sections, a signal for each section, a track circuit for each section, including a source of electromotive force and a track relay responsive to reversals of current, a line circuit for each section comprising two line wires extending through the track section, a source of electromotive force for the line circuit and a line relay responsive to reversals of current connected to the line wires, a reversing switch for each section operated by the signal for the following track section for reversing the flow of current in the circuit in which it is connected, means for connecting said reversing switch either into the track circuit or into the line circuit, a signal controlling circuit adapted to be controlled by either the track relay or the line relay, and means for switching the controlling circuit of the signal from one relay to the other.

8. In combination, a railway track divided into sections, each section being divided into sub-sections, a signal for each section, a track circuit for each sub-section including a source of electromotive force and a track relay responsive to reversals of current, a line circuit comprising two line wires parallel to the track sections, a source of electromotive force for the line circuit and a line relay responsive to reversals of current connected to the line wires, said line circuit being controlled by the track relay for each sub-section, means controlled by

the track relay of each sub-section except the first sub-section for reversing the flow of current through the track circuit of the preceding sub-section, a reversing switch for each section operated by the signal for the track section in advance for reversing the flow of current in the circuit in which it is connected, means for connecting said reversing switch either into the track circuit of the last sub-section or into the line circuit, a signal controlling circuit adapted to be controlled by contacts of either the track relay of the first sub-section or the line relay, and means for switching the controlling circuit of the signal from one relay to the other.

9. In combination, a section of railway track, a signal for the section stationed adjacent the entrance to the section, a track circuit for the section including a source of electromotive force and a track relay responsive to reversals of current, a line circuit extending through the section, a source of electromotive force for the line circuit and a line relay responsive to reversals of current connected to the line circuit, a current reversing device, means for connecting said reversing device either into the track circuit or into the line circuit, a caution circuit and a proceed circuit for said signal, both of said circuits being arranged so as to include either the contacts of the line relay or the contacts of the track relay, and means for switching the controlling circuits of the signal from one relay to the other.

10. In combination, a railway track divided into sections by means of insulated joints, and divided into sub-sections by means of additional insulated joints, a signal for

each section stationed adjacent the entrance to each section, a track circuit for each sub-section, including a source of electromotive force and a track relay responsive to reversals of current, a line circuit for each section comprising two line wires parallel to the section, a source of electromotive force for each line circuit and a line relay for each section responsive to reversals of current and connected to the line wires, said line circuit being controlled by the track relay for each sub-section, means controlled by the track relay of each sub-section except the first sub-section for reversing the flow of current through the track circuit of the sub-section in the rear, a reversing switch for each section operated by the signal for the track section in advance for reversing the flow of current in the circuit in which it is connected, means for connecting said reversing switch either into the track circuit of the last sub-section of the track section or into the line circuit, circuits for controlling each signal actuating mechanism one to operate the signal to give the caution indication and another to operate the signal to give the clear indication, both of said circuits being arranged so as to include either the contacts of the line relay or the contacts of the first track relay of the section, and means for each section for switching the controlling circuits of the signal from one relay to the other.

In testimony whereof I affix my signature in presence of two witnesses.

JOHN P. BUCHANAN.
